UNITED STATES PATENT OFFICE.

AMANDA C. BROWN, OF BROOKLYN, NEW YORK.

PROTECTIVE GARMENT.

1,418,526.

Specification of Letters Patent. Patented June 6, 1922.

Application filed July 31, 1920. Serial No. 400,368.

To all whom it may concern:

Be it known that I, AMANDA C. BROWN, a citizen of the United States, residing at the city of New York, borough of Brooklyn, 5 Kings County, in the State of New York, have invented certain new and useful Improvements in Protective Garments, of which the following is a full, clear, and exact specification.

10 My invention relates to improvements in wearing apparel, and the same has for its object more particularly to provide a protective garment for women, which may be conveniently adjusted over the usual skirt or 15 garment to be protected, and serve to envelope and protect the same.

Further, said invention has for its object to provide a neat, simple and efficient garment comprising an under, bag-like portion 20 which is adapted to receive and loosely support in raised position the skirt or garment of the wearer, and an outer, or skirt portion, attached to the under bag-like portion, serving to conceal the same, and the skirt 25 supported and confined within said bag-like portion.

Further, said invention has for its object to provide a protective garment comprising an outer or skirt portion, and an under, bag-like portion which is very loose or full so as 30 to receive and loosely support the usual skirt of the wearer, and cuffs at the lower ends of said bag-like portion adapted to be secured to and embrace the knees, and the portions 35 of the legs immediately adjacent thereto in order to maintain the enveloped skirt in raised position within said bag-like portion.

Other objects will in part be obvious and 40 in part be pointed out hereinafter.

To the attainment of the aforesaid objects and ends my invention consists in the novel details of construction, and in the combination, connection and arrangement of parts 45 hereinafter more fully described and then pointed out in the claims.

In the accompanying drawings forming part of this specification,

Figure 1 shows one form of garment constructed according to and embodying my said invention; said garment being shown in position upon the wearer, and partly broken away and in section in order more clearly to illustrate the same;

55 Fig. 2 is a front view of the garment, and

Fig. 3 is a back view the same, with the outer skirt portion partly broken away to disclose the bag-like under garment portion.

In said drawings 10 designates the garment as a whole comprising a very full, bag-like under portion 11, and an outer skirt or covering portion 12. The under portion 11 has separated openings at its lower edge to which are secured tubular portions or cuffs 13, 13 whose adjacent edges are provided 60 with suitable, cooperating fastening devices, such as buttons, 13a.

The upper edge of said bag-like under portion 11, is conformed to the hips and waist of the wearer and is provided with a 70 waist band 14 having a suitable fastening.

The back of said under portion 11 has a placket 15 whose overlapping edges are provided with stud and socket fastenings 16, 17 for securing the same together.

The outer or skirt portion 12 is secured along its upper edge by a row or rows of stitching 18 upon the outer side of the under portion 11 at a point corresponding substantially to the hip line of the wearer, and is provided at its rear with a placket 19, registering with the placket 15 of the under portion 11. The placket 19 is also provided with stud and socket fastenings 20, 21 for securing the same together.

To give the skirt portion 12 greater fullness, the same may be provided with one or more pleats 22, as shown.

In order partly to conceal the line where the upper edge of the skirt portion 12, is 90 secured to the bag-like under portion 11, pockets 23 are secured to the garment where the upper edge of the skirt portion 12 is secured to the under portion 11. The pockets 23 are provided at their opposite vertical 95 edges with upwardly projecting extensions 24 terminating at the waist band 14.

In use the garment is intended to be worn over the usual dress or gown as a protection therefor, and to this end the under portion 100 11 of the protective garment is first adjusted in position upon the wearer, and the cuffs 13, 13 fastened about the legs of the wearer. Hereupon the skirt of the dress or garment to be protected is gathered up and disposed 105 within the bag-like under portion 11, and the waist band 14 then fastened about the waist of the wearer, and both the bag-like under portion 11, and the outer, skirt portion 12 thereby supported properly in position.

tion upon the wearer leaving the legs practically free from the knees down.

It is to be noted that my improved protective garment is particularly useful where 5 the skirt of the garment to be protected is a tight or close-fitting one allowing of only limited freedom for the legs. By means of my garment the bottom edge of the garment may be raised to, and supported at or above 10 the knees, and thereby permit of greater freedom for the movement of the feet.

Further, it is to be noted that the protective garment may be made of thin, light material so as to occupy little space when the 15 same is not in use.

Having thus described my said invention, what I claim and desire to secure by Letters Patent is:—

1. A protective garment comprising a bag-like portion loosely enveloping the hips and thighs of the wearer and adapted to receive the skirt of a garment to be protected, openings in the lower edge of said bag-like portion, cuffs extending from said openings 25 and adapted to embrace the legs of the wearer at about the knees, means for securing said bag-like portion about the waist of the wearer, an outer skirt portion secured along its upper edge to said bag-like portion at a point below the waist band thereof, and means for securing said outer skirt portion together, substantially as specified.

2. A protective garment comprising a bag-like portion loosely enveloping the hips and thighs of the wearer and adapted to receive 35 and completely enclose the skirt of a garment to be protected, openings at the lower edge of said bag-like portions each adapted to receive one leg of the wearer, cuffs extending from said opening adapted to be 40 secured to the legs of the wearer at about the knees, a placket at the upper rear edge of said bag-like portion, means for securing the same together, and an outer skirt portion secured along its upper edge to said 45 bag-like portion at a point below the waist line of said bag-like portion, and a placket registering with the placket in said bag-like portion for securing said skirt portion in position to envelope and conceal the lower portion of said bag-like portion and the legs of the wearer, substantially as specified.

Signed at the city of New York, in the county and State of New York, this 23rd day of March, one thousand nine hundred 50 and twenty.
